UNITED STATES PATENT OFFICE.

VICTOR CARLSON, OF CHATCOLET, IDAHO

LIQUID-FEED GOVERNOR.

1,182,347.

Specification of Letters Patent.

Patented May 9, 1916.

Application filed June 1, 1915. Serial No. 31,435.

To all whom it may concern:

Be it known that I, VICTOR CARLSON, a citizen of the United States, residing at Chatcolet, in the county of Kootenai and State of Idaho, have invented certain new and useful Improvements in Liquid-Feed Governors, of which the following is a specification.

This invention relates to improvements in liquid feeding governors, especially adapted for liquid separating mechanism of the centrifugal type.

The invention relates more particularly to that class of governing feeding devices including a valve, controlling the flow to the separator, the valve being opened only after the separator has attained a predetermined speed. In this class of feeding devices it is important that the controlling valve operates instantly toward a closing position when the speed decreases from a predetermined standard and therefore it is one of the objects of this invention to provide a spring controlled valve, the spring acting normally to close the valve against the action of the governor to open the same. By means of this combination, the controlling valve is never opened until the governor positively actuates the same upon the attainment of said predetermined speed, and further, reliance is not placed upon the governor to close the valve when the speed lowers.

My invention also includes an improved speed indicator which may be adjustably connected for operation by the governor.

In order to enhance the sensitiveness of the device to sudden changes, due to varying speed, it is important to have a quick opening and closing movement of the controlling valve, therefore I have provided an improved closure having ingress and egress ports, preferably arranged to provide for equal liquid passage area, the ingress port being divided into a plurality of separate ports and arranged in such a manner that rotation of the closure to an extent less than would be sufficient to close the egress port, will be enough to close or open the ingress ports thereby always leaving the egress port open even when the valve is in a closed position.

My invention has many other objects and features which will be more fully described in connection with the accompanying draw-

ings which will be more particularly pointed out in and by the appended claims.

In the drawings:—Figure 1, is a perspective view of a cream separator showing the device of my invention applied thereto. Fig. 2, is a view in side elevation, with parts in section, showing my improved governor device. Fig. 3, is a detail view of the portion of the bracket on which my device is mounted. Fig. 4, is a sectional view on line 4—4 of Fig. 2. Fig. 5, is a view looking from the left of Fig. 2, illustrating the speed indicator in elevation and also showing the link connection between the controlling shaft and the controlling valve. Fig. 6, is a view in perspective of a portion of the bowl casing of the separator and showing the disposition of the controlling valve in the supply pipe. Fig. 7, is a sectional view on line 7—7 of Fig. 8. Fig. 8, is a sectional view on line 8—8 of Fig. 7. Fig. 9 is a sectional view on line 9—9 of Fig. 8.

Like characters of reference designate similar parts throughout the different figures of the drawings.

As illustrated, 1 designates a frame of the separator on which is mounted the bowl casing 2 having liquid discharge spouts 3 and 4 for the discharge of separated liquid.

A supply tank is indicated at 5 and communicates with the supply pipe 6 which delivers the liquid to be separated into the bowl. A controlling valve is indicated at 7 and is shown more particularly in Figs. 6, 7 and 8, to which reference will now be made. Said valve includes a valve casing 8, interposed in the pipe 6 near the discharge end of the latter. The casing 8 is provided with a rectangular ingress port which is preferably divided into two ports 9. Said casing is provided with an egress port 10 which comprises a single undivided opening of a liquid volume passage capacity equal to or substantially equal to the passage area of the ports 9. A rotary valve closure 11 is disposed in said valve casing and is provided with a cavity 12. The cavity 12 is provided with divided ingress ports 13, adapted to register with ingress ports 9, as shown in Fig. 7. Said valve closure 11 is also provided with a single egress port 14, adapted to register with egress port 10, of the casing 8.

It will be readily seen by reference to

Figs. 7 and 8, that rotation of the valve closure sufficiently to close the ingress side, will only be of an extent equal to the width of one of the narrow and elongated ingress ports 13. This short movement will either open or close the valve without the necessity of fully closing the single larger egress port 14. However, when the ingress ports 13 are in full registry with the ingress ports 9, the egress port 14 will be in full register with the egress port 10. It will now be seen that by reason of the relatively limited movement necessary, I obtain a very quick and responsive opening and closing movement of the controlling valve because of the short distance which it is required to move. While I have shown this feature embodied in a rotary valve, I do not consider that this feature of the invention is limited to an embodiment of this particular type of valve. It is an important matter in this class of devices to have all of the parts readily removable so that they may be maintained in a clean and sanitary condition and I have provided an advantageous structure whereby the closure 11 may be readily removed from its casing.

In the embodiment shown, the valve casing is provided with a flange 15 from which oppositely disposed hook shaped pins 16 project. A closure disk 17 is provided with elongated slots 18 adapted for projection therethrough of the pins 16 so that the hook ends will engage the surface of the disk 17 and hold the latter in the position shown in Fig. 8. Mounted upon the closure disk 17 is a journal bracket 19, of generally U-shaped construction, one limb 20 thereof being mounted upon the disk 17 and the other limb 21 thereof being disposed in spaced relation with respect to said disk. The closure 11 is provided with a closure stem 22 which is journaled in the closure disk 17 and also in the limbs 20 and 21 of the bracket 19. An operating arm 23 is fixed on the spindle for connection with apparatus presently to be described, and coil spring 24 is wound about the spindle 22 between the limb 21 thereof and said arm 23. One end of the coil spring 24, as indicated at 25, engages the bracket 19 and the other end 26, engages the arm 23 and urges the latter in a direction to close the valve. The arm 23 is provided with a cam-like stop 23', for engagement with the bracket 19, to limit relative movement of the arm with respect to the bracket when the valve has reached a closed position.

An important feature of my removable closure, resides in the fact that the pins and slots 16 and 18 are so arranged that the normal opening stress imposed on the operating arm 23 will act to lock the closure disk 17 to the valve casing. Furthermore, the spring 24 is tensioned so as to not exercise any

stress on the valve closure when the latter has reached a closed position.

Reference will next be made to my improved governing device for actuating the controlling valve.

A bracket 27 is provided with a slotted attaching portion 28 for removable anchorage to a portion 29, of the frame 1. Said bracket 27 is provided with a horizontal portion 30 having a depending journal 31. The bracket is offset at 32 to provide a journal bearing for shafts about to be described, and said bracket has a horizontal extension 33 in which is journaled a vertical disposed governor spindle. The improved governor includes a sleeve 34 which is journaled in 33, and in a bearing 35, formed in an extension of part 33. Shoulders 36 and 37 are formed on the sleeve 34 so that the latter will be held against longitudinal movement. A bevel gear 38 is mounted on or formed with the sleeve 34 and meshes with a bevel gear 39 mounted upon shaft 40. Shaft 40 is journaled in bearings 31 and 32 and carries a pinion 41 which is driven by a gear wheel 42, operated by the usual crank 43. A longitudinally movable governor spindle 44 is journaled in sleeve 34 for rotative movement therein as well as longitudinal movement. On the upper end of said spindle is mounted a governor bar 45 to which governor arms 46 are pivoted, as indicated at 47. The governor arms 46 are adjustably weighted in the usual manner, by balls 48. An expansively acting spring 49 is interposed between the sleeve 34 and the governor ball 45 so as normally to lift the latter and force the governor balls into the position shown in Fig. 2. Centrifugal action of the governor balls will act against the spring 49 to shift the spindle 44 longitudinally downwardly. In order to rotate the governor arms 46 I connect the latter by links 50 with a sleeve bar 51, the latter being fixed upon sleeve 44, the links 50 being pivoted to sleeve bar 51, at 52, and to the governor arms 46, at 53. Thus it will be seen that the rotatively driven sleeve 34 will rotate the governor arms and when the latter spread, the governor spindle 44 will be longitudinally depressed.

I will now describe the novel means by which longitudinal depression of the governor spindle may be communicated to the controlling valve and also to the speed indicating device which I will also presently describe.

A controlling shaft is indicated at 54 and is journaled in the offset portion 32 of the bracket 27 and also in the vertical portion 28 in said bracket. An arm 55 is rigidly mounted on said shaft 54 and is provided with a cranked end 56 extending beneath the governor spindle 44 so as to be engaged thereby. A spring 57 is trained about said

controlling shaft and has one end 58 connected with said arm 55 in such a manner as normally to engage the arm tightly against the lower end of spindle 44. The remaining end of said spring 57, as indicated at 59, engages the portion of the bracket 33. It will now be seen that centrifugal spreading movement of the governor arms will be resisted by the spring 49 and the spring 57.

10 On the outer end of the controlling shaft 54 is mounted an arm 60 to which is pivoted one end of a link 61, as indicated at 62. The link may be jointed, as indicated at 63, if desired. The remaining end of the link 61 is releasably connected, as at 64, with arm 23, and may be jointed, as indicated at 65. Now it will be seen that contra-clockwise adjustment of shaft 54 will serve to open the controlling valve and that a clockwise movement 15 of said shaft would tend to close the controlling valve. However, as before stated, reliance is not placed upon transmission of power from the governor to the controlling valve to close the latter, as the latter will be 20 instantly closed by its spring 24 as soon as stress on the arm 23 has been released.

A bracket 66 extends upwardly from bracket 27 and terminates in a graduated scale 67. A spindle 68 is mounted in said 30 bracket 66 and carries an index 69 adapted to traverse the graduated scale. An arm 70, mounted on said spindle 68, is connected at 71 with a link 72. The remaining end of link 72 is pivoted at 73 to an adjusting nut 74. This 35 adjusting nut 74 may include oppositely disposed nuts 75 which may be adjusted on a threaded arm 76, mounted on shaft 54, to give an accurate speed reading of the device. Thus the operator will merely have to glance 40 at the speed indicator to know whether or not he is operating the machine at the required speed which is necessary to give the maximum separating efficiency and the inlet to the bowl is automatically controlled so 45 that no liquid will be permitted to enter the bowl until a predetermined speed has been attained.

It is believed that the advantages and utility of my invention will be clearly understood from the foregoing description, and 50 while I have herein shown and described

one specific form of my invention, I do not wish to be limited thereto except for such limitations as the claims may import.

I claim:—

1. In a liquid feed controlling device, an inlet valve for controlling the flow and comprising a fixed valve casing, a rotatable valve closure in said casing provided with a stem, a closure disk loose on said stem and provided with a bracket fixed to said disk closure, an operating arm fixed to said stem and provided with a stop for engagement with said bracket to limit relative movement of said arm and bracket when valve closure is in a closed position, a spring normally acting upon said arm to close said valve, and a governor for opening said valve when the separator has attained a predetermined speed, substantially as described. 55

2. In a liquid feed controlling device, an inlet valve controlling flow and comprising a fixed valve casing, a rotatable valve closure in said casing provided with a stem, a closure disk loose on said stem and provided with a fixed bracket journaled in said stem, an operating arm fixed to said stem and having a stop for engagement with said bracket to limit relative movement of said arm and bracket, a spring connected with said arm and bracket to normally hold the same against movement when said valve has reached a closing position, a governor connected with said arm to open said valve when the separator has attained a predetermined speed, and 80 said casing and disk closure having loose pin and slot connecting means arranged to lock the disk closure on said casing when opening stress is imposed on said arm, substantially 85 as described. 90

3. In a liquid feed controlling device, an inlet valve controlling flow and comprising a casing and a closure in said casing, a disk closure free for movement with respect to said valve closure, an operating arm fixed 95 with respect to said valve closure, said casing and disk closure having loose pin and slot connection arranged to lock said disk against movement after the valve closure has reached a closing position, substantially as described. 100

In testimony whereof I affix my signature.

VICTOR CARLSON.
